UNITED STATES PATENT OFFICE.

VINCENT WANTE, OF WOONSOCKET, RHODE ISLAND.

STOP MOTION.

Application filed July 18, 1922. Serial No. 575,786.

To all whom it may concern:

Be it known that I, VINCENT WANTE, a citizen of the United States, residing at Woonsocket, in the county of Providence and State of Rhode Island, have invented 5 certain new and useful Improvements in Stop Motions, of which the following is a specification.

My invention relates to stop motions for 10 gill boxes and has for its essential objects the detection of any slack or clogging of the traveling slivers and the stopping of the mechanism when event occurs; adaptability for use without incorporation into the machine and without reconstruction of the latter; portability; and certainty and speed of 15 operation.

To the above ends essentially my invention consists in such parts and in such combinations of parts as fall within the scope 20 of the appended claims.

In the accompanying drawings which form a part of this specification,

Figure 1 is a rear elevation of a gill box, 25 and of the stop motion mechanism, showing the electric wiring diagrammatically,

Figure 2, a plan of the knock off mechanism of my stop motion including the magnet housing,

Figure 3, a plan of the latter with the housing top removed,

Figure 4, a section on line 4—4 of Figure 2,

Figure 5, a front elevation of the knock 35 off mechanism,

Figure 6, a fragmentary perspective view of a portion of the same,

Figure 7, a vertical central section of the electric switch showing adjacent portions in side elevation,

Figure 8, a partial section on line 8—8 of Figure 1,

Figure 9, a fragmentary plan view of the knock off mechanism showing the position 45 of parts preparatory to unseating the lever,

Figure 10, a diagrammatic view of the entire stop motion mechanism,

Figure 11, an enlarged rear elevation of the detector mechanism, and

Figures 12 and 13, sections of the same

on lines 12—12 and 13—13 respectively of Figure 11.

Like reference characters indicate like parts throughout the views.

In the drawings 17 represents the frame, 55 18 the driving shaft, 19 the pulleys, 20 the belt, 21 the fork, 22 the shifting rod, 23 the bell crank lever, and 24 the hand operating rod of a gill box of any usual or preferred construction.

26 is the disk, and 27 the peripherally 60 slidable strap of an eccentric 28 which is mounted on the driving shaft. An inclined reciprocating finger 30 is fast to the strap. Below the latter is a portable frame comprising a horizontal strip or plate 32 having a depending lateral flange 34. The strip 32 has an oblong slot 35 with a lateral recess 36 forming a resultant shoulder 37, and is supported at its ends by diverging legs 38 resting upon the floor 39. An oblong plate 40 is attached to the rear of the frame by bolts 41 passing through the flange 34 and is spaced from the latter by collars 42 forming a resultant oblong opening 43. Fast 65 to the rear face of the plate 40 midway its length is an ear or lug 45 having a vertical oblong slot 46 in its upper portion, below which is fast an outwardly extending horizontally disposed rod 48 carrying an anti-friction roller or bearing sleeve 50 for the finger 30. Fastened by bolts 54 to the plate 32 is a depending flat rod 56 bent at its lower end to form a U shaped portion 57 extended to form an upright resilient arm 80 58 whose upper portion 59 projects through the slot 35 and forms an operating handle in the path of a finger 60 extending from the shifting fork 21.

Plates 61 are clamped to opposite faces of 90 the arm 58 by screws 63, one of which plates has a guide pin 64 registering loosely in a longitudinal slot 66 in a flat rod 67 to whose opposite end is pivoted by a pin 68 a lever 69 which passes through a peripheral 95 slot 70 in a cylindrical switch casing or housing 71. The lever is pivoted intermediate its length on a pin 73 in the end walls of the housing. Fast to one of these walls is a strap 75 embracing the rod 56 fixing the 100

- housing to the latter. A wire spring 77 has one end attached to the side wall of the housing by a screw 78 while its opposite end is fastened to the lever 69 by a bent end 5 79 passing through a perforation 80. An insulating block 82 is fastened by screws 83 to the lower portion of the housing wherein is a hole 84, registering with a vertical passage 85 in the block, and with a hole 86 10 in a metal plate 87 fastened by a screw 88 to the top of the block. Integral with the plate is an inclined contact arm 89 in the path of the lever 69. There is a binding screw 91 in the plate 87 and like screw 92 15 in a housing which respectively engage a conductor 94 which passes through the holes 84, 85, and 86, and a conductor 95. The arms 69 and 89 constitute a switch indicated generally by 96.
- 20 Loose on a pin 97 in the flange 34 at one side of the ear 45 is an angular lever comprising a body 99 and arms 100 and 101. The pin 97 passes loosely through a vertical oblong opening 103 in the flange 34 and having a head 104 upon one end engaging the lever, and a disk or nut 105 upon the other end. A helical spring 107 on the pin has one end pressing against the flange 34 and the other against the disk 105. By this construction the angular lever has not only pivotal movement transversely of the pin, but is yielding longitudinally thereof. On the arm 100 is a lateral spacing plate 109. To the arm 101 is loosely pivoted by a pin 110 25 the upper end of a depending flat link 111 having near its lower end a longitudinal series of holes 113 adapted to receive a threaded pivot pin 115 in the outer end of an armature lever 117. On the pin is a nut 118.
- 30 The lever 117 passes through an opening 119 in an end wall of a wooden box or casting 121, and through lateral openings 123 in a housing 125 fastened by a screw 126 to a wooden cross piece 127 in the box top. The lever 117 is pivoted on a pin 129 fast in the housing and has intermediate the pivotal point and its free end a laterally projecting portion 130 adapted to register with the cores 132 of a magnet 133 whose spools 134 35 are wound from the wire 95, passing through an opening 135 in the box. Upon the end of the armature lever is a counterweight 136 adjustable by a set screw 137. Extending from the spools of the magnet through the opening 135 is a conductor 139 leading to a battery or other source of electrical power, in this instance to a transformer 141 connected by wires 142 and 143 to the wires 144 and 145 respectively of a power circuit.
- 40 Resting on the body 17 of the machine is a frame work 148 comprising open metallic vertical end pieces or frames 150 with a top cross bar 152 and bottom cross bars 154. Each frame is filled with a wall or plate 156 45 of insulating material covered by hollow or flanged wooden sheathing strips 158 registering in the frames 150 and attached to the insulating strips by screws or bolts 160. Transversely disposed metal strips or plates 162 are fastened, one above the other, to the inner face of each wall 156, and each plate has a longitudinal series of holes 164 registering with series of holes 165 in the walls. Mounted in the holes 164 and 165 are rock shafts 166 having in their ends lock pins 168 to whose ends are attached helical springs 169 whose upper ends are fastened to pins 170 in the walls 156 above the shafts. Each shaft carries a guide 171 for a length of sliver 172 passing from the usual supply balls to the winding roll of the gill box; the balls and roll are not shown. Each sliver comprises the usual mass of threads. Each guide comprises a pair of legs 174 formed from bent wire whose free ends are fast to 50 the rock shafts 166 and inclined upwardly some distance and thence downwardly at an incline as at 175 and terminate in horizontal loops 176. These guides are completed by troughs 177 bent up from sheet metal comprising downwardly inclined bottoms 178 and vertical sides 179. Integral sleeves 180 and 181 on the bottoms and sides respectively embrace the loops 176 and arm portions 175. The slivers pass through the trough portions of the members 171 and by their weight in passing overcome the resistance of springs 169 and maintain the members 171 against longitudinally disposed stop rods 184 fixed to the frames 150 above the planes of the shafts 166 by screws or rivets 185. If however any sliver 172 becomes broken or slack its guide is raised by its spring 169 until it engages a contact rod 187. There is one metallic contact rod fast in walls 156 above each series of shafts 166 in a horizontal plane above the stop rods 184. A longitudinally split removable tube 189 of rubber or insulating material is sometimes temporarily employed on the rods 187. Such a tube is shown in Figure 11. The ends of the rods 187 project slightly beyond the insulating walls and are there connected by electric wires 191. A binding screw 193 of each plate 162 passes through the wall 156 and carries a nut 194 to clamp a wire 196 which thus electrically connects the series of shafts 166 through the plates 162. One wire 196 constitutes a section of the conductor 94. One wire 191 extends from the rods 187 to the transformer 141. The wires 94 and 191 emerge through a hole 199 in one of the strips 158. 55
- 60 The operation of my stop mechanism is as follows. Normally the automatic shift lever 59 is in the position shown in Figure 9 resting in its recess 36 and held against the action of its spring loop portion 57 by the 65
- 70
- 75

shoulder 37. This lever is also in contact with the finger 60 upon the shifting fork 21 which is at this time engaging the belt on the fast pulley, and the plunger finger 30 is continuously reciprocating towards and from lever 59 by virtue of the eccentric 30. The spacer 109 is normally in the position shown in Figure 6 so that while the machine is running normally the spacer is out 10 of the path of the reciprocating finger 30.

When, however, the stop motion acts, as will be later described, the spacer 109 is swung forwardly into the path of the finger 30 as shown in Figure 9 and the finger in its 15 next advance strikes the side of the laterally yielding spacer 109, which is now abutting against the lever 59, and pushes the latter out of its seat. Thereupon the lever is forcibly impelled by the action of its spring 57 20 against the finger 60 which shifts the fork 21 to the loose pulley, as shown in Figure 2, thus stopping the machine.

The spacer 109 is thrown in operative stopping position thus. When one of the 25 cables or slivers 172 in its passage to the winding roll becomes slack so as to occasion clogging or folding of the sliver its guide 171, released from the weight of the sliver, is by its spring 169 forced 30 upwardly so that its legs 174 contact with its adjacent bar 187, thus closing the electric circuit. The current then passes through the conductor 191, rod 187, arms 174, rock shaft 166, strip 162, wires 196, 35 94, and through the closed switch 96 wherein the arms 69 and 89 are in contact with each other. The current passes, therefore, through the plate 87, arms 89 and 69, pin 73, housing 71, and wires 95 and 139. The 40 current energizes the magnet 133 to tilt the lever 117, which depresses the link 111 and lever arm 101 and swings the spacer 109 into operating position.

The instant the lever 59 is unseated and 45 swings to its outward limit the circuit is broken by the separation of the arm 69 from the arm 89 as shown in Figure 6.

The particular number of guides 171 in use at any given time is determined by the 50 number of strands desired to be wound from the supply rolls. Therefore at times one or more horizontal rows of guides are not in use. In such case the bar 187 above the line of idle guides has manually applied thereto 55 an insulating tube 189 against which the vacant arms of the guides normally rest so that the circuit is not closed thereby.

I claim:

1. In a gill box, the combination with the 60 main shaft and shifter fork, of a reciprocating finger carried by the shaft, a resilient shifting arm seated adjacent the finger adapted when unseated to swing against the fork, and a laterally yielding spacer mov-

able into and out of the path of the finger 65 adjacent the lever, and means controlled by a sliver for actuating the spacer to receive the impact of the finger and unseat the lever.

2. In a gill box, the combination with the 70 main shaft and shifter fork, of a reciprocating finger carried by the shaft, a support adjacent the shaft provided with a slot below the fork, and with a recess at one end of the slot in alignment with the finger, 75 a resilient shifting arm comprising a rigid portion fast to the support and a resilient portion projecting above the support detachably seated in the recess, a two arm lever pivotally mounted on the support, between the slot and the shaft, a spacing plate on one of the arms of the pivoted lever movable between the finger and the seated portion of the shifting arm, a link attached to the second arm of the pivoted lever, an 80 armature attached to the link, a magnet adjacent the armature, an electric circuit including the magnet, a contact rod in the circuit, a yielding guide for a sliver in said circuit engagable with the rod to close the 85 circuit and energize the magnet and move the armature.

3. In a gill box, the combination with the 90 main shaft and shifter fork, of a reciprocating finger carried by the shaft, a resilient shifting arm detachably seated adjacent the finger in the path of the fork, a rocking spacer movable into and out of the path of the finger for unseating the lever, an electric circuit, a contact rod in the circuit, a 95 yielding guide for a sliver in the circuit adapted to engage the rod to close the circuit when a sliver becomes slack, a magnet in the circuit for actuating the spacer when the circuit is closed, and a normally closed 100 switch in the circuit adapted to be opened by the unseating of the shifting arm.

4. In a gill box, the combination with the 105 main shaft and shifter fork, of an eccentric on the shaft, a peripheral finger on the eccentric, a spring shifting arm detachably seated adjacent the finger in the path of the fork, a reciprocable spacer movable between and away from the lever and finger for unseating the lever, an electric circuit, a frame 110 comprising side walls of insulating material, contact rods in the circuit and connecting the walls, transverse metal strips in the circuit on the walls below the rods, rock shafts in the strips, resilient means for rocking the 115 shafts, guides fast to the shaft normally depressed by slivers passing thereover and engagable with the rods to close the circuit when the slivers are slack, and means in the circuit operated by the closure thereof for 120 actuating the spacer.

5. In a gill box, the combination with the 125 main shaft and shifter fork, of a recip-

roating finger carried by the shaft, a resil-
ient shifting arm detachably seated adjacent
the finger in the path of the fork, a recip-
rocable spacer movable into and out of the
5 path of the finger for unseating the lever,
an electric circuit, a frame comprising side
walls, contact rods arranged in vertical se-
ries in the walls of the circuit, a tube of in-
sulating material detachably mounted on one
10 of the rods, rock shafts mounted in the walls
adjacent the rods and in the circuit, guides

for the slivers fast to the shafts, resilient
means for rocking the shafts, to engage the
guides with the uncovered rods in the cir-
cuit when the slivers are slack whereby the 15
circuit is closed, and means in the circuit
operated by the closure thereof for actuat-
ing the spacer.

In testimony whereof I have affixed my
signature.

VINCENT WANTE.
